Primary Examiner — Garth Rademaker*Assistant Examiner* — Samantha Q Lawrence(74) *Attorney, Agent, or Firm* — Nixon & Vanderhye, P.C.(57) **CLAIM**

The ornamental design for an air delivery tube with cuff, as shown and described.

DESCRIPTION

FIG. 1 is a front perspective view of an air delivery tube with cuff according to our new ornamental design;

FIG. 2 is a rear perspective view thereof;

FIG. 3 is a top view thereof;

FIG. 4 is a front view thereof;

FIG. 5 is a right side view thereof; and,

FIG. 6 is a left side view thereof.

The broken lines shown in FIGS. 1-6 illustrate portions of the air delivery tube with cuff that form no part of the claimed design.
